(57) **CLAIM**

The ornamental design for an LED eye care device, as shown and described.

DESCRIPTION

FIG. 1 is an isometric view of an LED eye care device according to my new design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

(Continued)

The LED eye care device of the present invention is used by a user to treat fine lines, wrinkles and dark circles around the eyes.
